WOOD BURNING HEATER

Robert L. Stevenson, 9003 W. Evans Creek Road,
Rouge River, Oreg. 97537

Filed May 4, 1972, Ser. No. 250,470

Term of patent 14 years

Int. Cl. D23—03

U.S. Cl. D23—93

Fig. 1

Fig. 2

Fig. 3

Fig. 4

Fig. 5

Fig. 6

FIG. 1 is a side elevational view of a wood burning heater showing my new design;

FIG. 2 is an opposite side elevational view thereof;

FIG. 3 is a top plan view thereof;

FIG. 4 is a bottom plan view thereof;

FIG. 5 is an end view taken from the right side as viewed in FIG. 1; and

FIG. 6 is an end view taken from the left side as viewed in FIG. 1.

The rectangular panel in FIG. 1 is shaded with oblique lines to indicate transparency.

I claim:

The ornamental design for a wood burning heater, as shown and described.
